UNITED STATES PATENT OFFICE.

GEORGE P. WIGGINTON, LEON L. ALLYN, AND NICHOLAS H. STUART, OF KALAMAZOO, MICHIGAN, ASSIGNORS TO KALAMAZOO LOOSE LEAF BINDER COMPANY, OF KALAMAZOO, MICHIGAN.

LOOSE-SHEET DEVICE.

Application filed February 6, 1925. Serial No. 7,293.

To all whom it may concern:

Be it known that we, GEORGE P. WIGGINTON, LEON L. ALLYN, and NICHOLAS H. STUART, citizens of the United States, residing at the city and county of Kalamazoo, State of Michigan, have invented certain new and useful Improvements in Loose-Sheet Devices, of which the following is a specification.

10 This invention relates to improvements in loose sheet devices. Our improvements are especially designed for the handling of loose sheets in accounting or record systems.

15 The main object of this invention is to provide an improved loose sheet device which enables the rapid and efficient manipulation of loose sheets in the making of entries or records thereon and also to provide a secure binding for filing or reference purposes which permits the handling of the used sheets as a unit.

20 Objects pertaining to details and economies of our invention will definitely appear from the detailed description to follow.

25 We accomplish the objects of our invention by the devices and means described in the following specification. The invention is clearly defined and pointed out in the claims.

30 A structure embodying the features of our invention is clearly illustrated in the accompanying drawing forming a part of this application, in which:

35 Fig. I is a perspective view of a loose leaf binder of the type we preferably employ as an element of the device.

Fig. II is a perspective view of a sheet support forming another element of the device.

40 Fig. III is a vertical longitudinal section of the sheet support with sheets arranged therein, the adjustment of the side member of one of the holders being indicated by dotted lines, the section being taken on line 45 3—3 of Fig. IV.

Fig. IV is a plan view of the parts shown in Fig. III.

Fig. V is a perspective view of the binder open to permit the removal of the sheet body as a unit.

Fig. VI is a perspective view of the sheet body removed from the binder with indicia sheets inserted between the record sheets.

50 Fig. VII is a sectional view on a line 55 corresponding to line 7—7 of Fig. VI.

Fig. VIII is a perspective view of one of the removable post bars.

In the drawings the sectional views are taken looking in the direction of the little arrows at the ends of the section lines and similar numerals of reference indicate similar parts throughout the several views.

Referring to the drawings, the sheets 1 are provided with holes 2 adjacent their binding edges and notches 3 in their binding edges. The holes 2 are spaced to receive the posts 4 of the post bars 5. These post bars also have notches 6 alined with the notches 3 to receive the binding strips 8 of the binder, which, in the structure illustrated comprises 70 a pair of covers 9 having clamping bars 10 hinged thereto, the covers being adjustably connected by means of the flexible strips 8.

The post bars have pins 11 adapted to engage the holes 12 in the clamping bars thereby retaining the sheets within the binder when the binder is closed and permitting the removal of the sheet body with the post bars or binding means as a unit. This binder structure is, so far as removable post 80 bars are concerned, substantially the same as that of the Wigginton Patent No. 1,410,788, dated March 28, 1922.

To facilitate the manipulation of the sheets in accounting or machine bookkeeping, we provide a support designated generally by the numeral 13 and comprising a pair of V-shaped holders 14 and 15. The holder 14 comprises the side member 16 and end member 17 disposed at right angles 90 thereto. The holder 15 comprises the side member 18 and end member 19. The side member 18 is hinged at 20 and adjustably supported by the pivot 21 so that it may be adjusted to a position at right angles to the end member as shown by full lines in Fig. 95 III, or to a position forming an acute angle relative to the end member 19, the purpose of this adjustment being to support the sheets with their edges abutting the end member so that their outer edges may lie as shown or may be stepped or fanned to facilitate fingering.

The end members 17 and 19 project beyond the side members at one end and are provided with sheet alining guides 22 on such projecting ends so that the sheets may be arranged in either holder with their side edges abutting the end members and their binding edges abutting these guide ribs, the 110

binding edges of the sheets projecting beyond the side members of the holders to permit the removal or insertion of the post or engagement or disengagement of other binding means with the sheets.

In practice the sheet body is arranged in the holder 15 with the side member 18 adjusted to its lowered or right angled position relative to the end member. The side member is then adjusted to the dotted position shown in Fig. III which "fans" the upper edges of the sheets facilitating finger-
10 ging so that the desired sheet or sheets may be lifted from the holder 15 for transferring
15 to the holder 14.

In practice the operator, prior to beginning the posting operation, "stuffs" the sheets by inserting the memoranda such as sales slips or the like, or other indicia which
20 are to be added to the record sheets, in proper place so that as the sheets are lifted from the holder, the memoranda are available with the sheets. It is the usual practice to check the entries after the same have
25 all been made, and for convenience in checking, the memoranda or indicia sheets are placed with the record sheets in the holder 14. In order that they may be arranged in projecting relation when the sheet body is removed from the holder, we provide a recess or pocket 23 in the end wall 17 which allows the indicia sheets to drop below the lower edges of the record sheets, the ends of the indicia sheets being supported by the
30 wall of this pocket or recess, so that when the sheets are removed from the holder as shown in Fig. VII the markers or indicia sheets project to indicate where entries have been made, and also that the entries may be rapidly and conveniently checked with the
35 respective memoranda sheets.
40

This is of great practical advantage in the manipulation of the sheets and memoranda to be entered thereon and in the checking or re-checking of the same by the person making the entries, or by others.

We have illustrated and described our invention in embodiments which we have found to be very practical, the particular binder and binding means illustrated being the form commercially used by us. Other forms of binders, however, such as post binders might be employed. We have not attempted to illustrate the various types of binders which might be employed or other modifications which we contemplate as we believe the disclosure made will enable those skilled in the art to embody or adapt our invention as may be desired.

Having thus described our invention what we claim as new and desire to secure by Letters Patent is:

1. The combination with record sheets, of a binder provided with sheet binding means removable from the cover whereby the sheet

body bound together as a unit by such binding means may be removed from or placed in the cover as a unit, and a sheet support comprising a pair of sheet holders having side and end members disposed so that the
70 sheets may be arranged on the side members with their side edges abutting said end members, said end members projecting beyond the side members at one end and having sheet alining guides on the projecting ends
75 positioned so that the binding edges of the alined sheets project beyond the side members permitting the engagement and disengagement of the binding means therewith while in the holder, one of said end members having a recess therein to receive the projecting ends of sheets disposed between the record sheets.

2. The combination with record sheets, of a binder provided with sheet binding means removable from the cover whereby the sheet body bound together as a unit by such binding means may be removed from or placed in the cover as a unit, and a sheet support comprising a pair of sheet holders having side and end members disposed so that the
80 sheets may be arranged on the side members with their side edges abutting said end members, said end members projecting beyond the side members at one end and having sheet alining guides on the projecting ends
85 positioned so that the binding edges of the alined sheets project beyond the side members permitting the unobstructed engagement and disengagement of the binding means therewith from above and from below while in the holder.

3. The combination with record sheets, of a binder provided with sheet binding means removable from the cover whereby the sheet body bound together as a unit by such binding means may be removed from or placed in the cover as a unit, and a sheet support comprising a pair of sheet holders having side and end members disposed so that the
90 sheets may be arranged on the side members with their side edges abutting said end members, one of said end members having an opening therein to receive the projecting ends of markers disposed between the sheets, the side member of the other holder being
95 adjustable relative to its coacting end member to a position at right angles thereto or to an angle less than a right angle, for the purpose specified.

4. The combination with record sheets, of a binder provided with sheet binding means removable from the cover whereby the sheet body bound together as a unit by such binding means may be removed from or placed
100 in the cover as a unit, and a sheet support comprising a pair of sheet holders having side and end members disposed so that the sheets may be arranged on the side members with their side edges abutting said end mem-

bers, one of said end members having a opening therein to receive the projecting ends of markers disposed between the sheets.

5. The combination with record sheets having holes adjacent their binding edges, of a binder provided with removable post bars having posts engageable with said holes in said sheets whereby the sheet body while bound with said post bars may be removed from or placed in the cover as a unit, and a sheet support comprising a holder having side and end members disposed so that the sheets may be arranged on the side members with their side edges abutting said end members, said end members projecting beyond the side members at one end of the holder and having a guide on their projecting ends coacting with the edges of the sheets to aline the same to receive said binding posts, one of 10 said end members having an opening to receive the projecting ends of markers disposed between the sheets.

6. The combination with record sheets having holes adjacent their binding edges, 25 of a binder provided with removable post bars having posts engageable with said holes in said sheets whereby the sheet body while bound with said post bars may be removed from or placed in the binder as a unit, and a sheet support comprising a holder having side and end members disposed so that the sheets may be arranged on the side member with their side edges abutting said end member, said end member projecting beyond the side member at one end of the holder and having a guide on its projecting end coacting with the edges of the sheets to aline the sheets with their binding edges projecting beyond the side members to permit the engagement or removal of the binding posts therewith from above or below the sheets.

7. The combination with sheets, of removable binding means, and a sheet support comprising a holder having side and end members disposed so that the sheets may be arranged on the side member with their side edges abutting said end member, said end member projecting beyond the side member at one end of the holder and having a guide 40 on its projecting end coacting with the edges of the sheets to aline the sheets with their binding edges projecting beyond the side members to permit the engagement or removal of the binding posts therewith from above or below the sheets.

8. The combination with sheets, of removable binding members, and a sheet holder having side and end members disposed so that the sheets may be arranged on the side member with their side edges abutting the end member, said holder being provided with sheet alining means whereby the alined sheets are supported with their binding edges projecting to facilitate the engagement and disengagement of the binding

members therewith, said end member having an opening therein to receive projecting ends of markers disposed between the sheets.

9. The combination with sheets, of removable binding members, and a sheet holder 70 having side and end members disposed so that the sheets may be arranged on the side member with their edges abutting the end member, said end member having an opening therein to receive projecting ends of markers disposed between the sheets.

10. A sheet support comprising a pair of sheet holders having side and end members disposed so that the sheets may be arranged on the side members with their side edges abutting said end members, said end members projecting beyond the side members at one end and having sheet alining guides on the projecting ends positioned so that the binding edges of the alined sheets project 80 beyond the side member permitting the engagement and disengagement of sheet binding means therewith while in the holder, one of said end members having a recess 90 therein to receive the projecting ends of markers disposed between the sheets, the side member of the other holder being adjustable relative to its coacting end member to a position at right angles thereto or to an angle less than a right angle, for the purpose specified.

11. A sheet support comprising a pair of sheet holders having side and end members disposed so that sheets may be arranged on the side members with their side edges abutting said end members, said end members projecting beyond the side members at one end and having sheet alining guides on the projecting ends positioned so that the binding edges of the alined sheets project beyond 100 the side member permitting the engagement and disengagement of sheet binding means therewith while in the holder from above or below the projecting ends of the sheet, the side member of the other holder being adjustable relative to its coacting end member to a position at right angles thereto or to an angle less than a right angle, for the purpose specified.

12. A sheet support comprising a pair of sheet holders having side and end members disposed so that sheets may be arranged on the side members with their side edges abutting said end members, said end members projecting beyond the side members at one end and having sheet alining guides on the projecting ends positioned so that the binding edges of the alined sheets project beyond 115 the side member permitting the engagement and disengagement of sheet binding means therewith while in the holder, one of said end members having a recess therein to receive the projecting ends of markers disposed between the sheets.

13. A sheet support comprising a pair of

- sheet holders having side and end members disposed so that the sheets may be arranged on the side members with their side edges abutting said end members, one of said end members having an opening therein to receive the projecting ends of markers disposed between the sheets, the side member of the other holder being adjustable relative to its coacting end member to a position at right angles thereto or to an angle less than a right angle, for the purpose specified.
14. A sheet support having side and end members disposed so that sheets may be arranged on the side member with their side edges abutting said end member, said end member having a guide coacting with the sheets to aline the same, said end member having an opening therein to receive the projecting ends of markers disposed between the sheets.
15. A sheet holder comprising side and end members disposed so that sheets may be arranged on the side member with their edges abutting said end member, said end member having a recess therein adapted to

receive the projecting ends of markers disposed between the sheets, the rear wall of the recess constituting a support for the projecting ends of the markers.

16. A sheet holder comprising side and end members disposed so that the sheets may be arranged on the side member with their edges abutting said end member, said end member having an opening therein adapted to receive the projecting ends of markers disposed between the sheets.

17. The combination with sheets, of a sheet holder having side and end members so that the sheets may be arranged on the side members with their edges abutting the end member, said end member having a recess therein adapted to receive the projecting end of markers disposed between sheets, said recess having a supporting bottom for said markers.

In witness whereof we have hereunto set our hands.

GEORGE P. WIGGINTON.
LEON L. ALLYN.
NICHOLAS H. STUART.
